Minneapolis, Minn., a corporation of Minne-
sota

Application December 21, 1931, Serial No. 582,305

3 Claims. (Cl. 68—9)

This invention relates to improvements in pressing machines which are well adapted for use on garment presses. Among the objects of the invention are to provide pressing elements between which the maximum conduction of heat may be had, and in which the walls of the pressing elements have a minimum thickness and a maximum of strength due to the introduction of means by which heat conduction to the pressing surfaces is accelerated. By the use of the invention, less steam pressure is required and the pressing time is materially lessened, because of the increased efficiency in the transmission of heat. Moreover, the heat-transmitting ribs act to reinforce the structures, so that considerably less metal is required in their construction, and thus the weight and, therefore, transportation costs are materially reduced. The invention herein is also shown, but not claimed, in an application by myself and another, Serial Number 520,850 for laundry press.

Features of the invention include all the details of construction disclosed, as well as the broader features relating to means which act, as the elements approach pressing position, to increase heat conduction, and also act to obtain a maximum of heat conduction to the pressing surfaces while the elements are performing the pressing operation.

Objects, features and advantages of the invention will be set forth in the description of the drawings forming a part of this application, and in said drawings

Figure 1 is a vertical transverse section through a press, showing one embodiment of the invention in which the ribs extend longitudinally of the pressing elements and associated parts, and showing the parts positioned as during the pressing operation;

Figure 2 is a detail section transversely of the pressing elements showing the position of the pad-carrying shell when the presser head is retracted;

Figure 3 is a plan section with the parts positioned as in Figure 1, and with parts broken away to expose some portion of each of the pressing and heat-transferring elements;

Figure 4 is a vertical longitudinal section taken approximately on line 4—4 of Figure 3;

Figure 5 is a vertical transverse section of a modification in which the upper wall of the lower steam chest is interiorly provided with longitudinally extending depending ribs, in addition to upstanding ribs on the upper surface of its upper wall;

Figure 6 is a modification in which the ribs of the shell and chest extend transversely, and showing the elements in their separated condition as when the presser head is retracted; and

Figure 7 is a longitudinal section of the construction of Figure 6.

The frame of the pressing machine is indicated at 1, and to this frame is attached the table support 2 having thereon a pedestal 3, which supports the buck or lower and stationary steam chamber 4. The chamber has suitable passages 6 arranged to obtain the proper circulation of steam. Steam pipes have not been indicated.

Spaced above the chest 4, and connected to the chest for vertical movement, is a cap or shell 10 having ventilating perforations 11. Upon this shell is arranged the usual padding 12. This shell 10 is arranged in spaced relation to the marginal portions of the chest 4, and is normally held in vertically spaced relation thereto by means of suitably arranged coil springs 13, arranged in sockets 14. The cap is thus adapted to be depressed as the presser head 15 continues to descend after engagement with the pad 12. The presser head is carried by the usual presser arm 16 pivoted as at 17 to an upward extension 18 of the frame 1. By this spacing, atmospheric communication with the space between the elements and through the openings is maintained between the chest 4 and shell. The present invention is well adapted to a device wherein a movable element, which is the equivalent of shell 10, is used.

The upper surface of the lower steam chest is provided with longitudinally disposed and transversely spaced vertical ribs or fins indicated at 20, the general arrangement of these fins, with reference to the springs 13 and sockets 14 is shown in Figures 3 and 4. The shell 10 is provided with longitudinal transversely spaced depending fins 21, the lower ends of which, when pressing force is not applied to the pad 12 to depress the element 10, lie at a level above the upper ends of fins 20, see Figure 2. Each fin 21 is arranged substantially midway between two fins 20 and it will be noted, in Figure 1, that on depression of the shell 10, the fins 21 are brought into closer proximity of the fins 20, thus substantially facilitating heat transfer between the fins, which continues throughout the pressing period. The ribs also perform the function of stiffening the walls of the hollow elements 4 and 10 so that the thickness of the walls of these elements can be made much less.

In certain sizes of presses, it was erstwhile necessary that the thickness of the metal be about three-eighths of an inch, while now, by the use of the present device, the thickness can 5 be safely reduced to a quarter of an inch or less. The elements weigh considerably less, and considerable less quantity of metal is required so that the cost of production is materially reduced.

10 The steam chest or head 15 is also provided interiorly with upstanding ribs 23 which act to materially increase the transmission of heat to its pressing surface 24. In this instance, these ribs are arranged longitudinally in conformity to 15 the arrangement of the ribs 20-21.

Suitable linkage bolts, in threaded connection with the shell, pass loosely through the lower walls of the sockets 14, and also pass loosely through the springs. The heads of these bolts 20 act to limit the upward motion of the shell.

Figure 5 shows a modification in which the lower steam chest 4 is additionally provided interiorly with depending ribs 30, the ribs being arranged longitudinally as in the first case. By 25 this means increased conduction is obtained over that obtained by the use of the upper ribs 20 alone. Figure 6 shows a modification in which ribs 31 of the lower steam chest 4 are arranged transversely and in which the ribs 32 30 of the shell 10 are arranged in like manner. Figure 7 shows the relation of the upper and lower ribs 31-32. In both figures, the shell 10 is shown in its uppermost position.

35

80

The invention is applicable to any kind of press in which two members cooperate in a fabric pressing operation.

I claim as my invention:

1. In a laundry press, the combination of a steam chest, and a pad-supporting element connected to the chest and movable with respect thereto during pressing action, said chest and pad-supporting element having ribs adapted to cooperate for increasing heat transmission during pressing action. 85

2. In a laundry press, the combination of a steam chest, and a pad-supporting element connected to the chest and movable with respect thereto during pressing action, said chest and pad-supporting element having ribs adapted to cooperate for increasing heat transmission during pressing action, and said pad-supporting element having ventilating openings which lie between its ribs. 90

3. In a laundry press, the combination of a hollow stationary pressing element, a pad-supporting element movable there-toward during pressing action, said elements having ribs adapted to increase conduction of heat to the 100 pressing point, the ribs of the pad-supporting element being arranged to enter and lie between the ribs of the stationary element and to be spaced therefrom during the pressing operation. 105
